UNITED STATES PATENT OFFICE.

CHARLES A. POMERENING, OF WAUZEKA, WISCONSIN.

SNAP-HOOK.

SPECIFICATION forming part of Letters Patent No. 372,817, dated November 8, 1887.

Application filed April 18, 1887. Serial No. 235,218. (No model.)

To all whom it may concern:

Be it known that I, CHARLES A. POMERENING, a citizen of the United States, residing at Wauzeka, in the county of Crawford, State of Wisconsin, have invented certain new and useful Improvements in Snap-Hooks, of which the following is a specification, reference being had therein to the accompanying drawings.

This invention has relation to snap-hooks, and among the objects in view is the provision of a combined snap-hook and buckle that may be easily and conveniently made in a single casting or piece that is cheap, strong, and durable.

Other objects and advantages of the invention will appear in the following description, and the novel features thereof will be particularly pointed out in the claims.

Referring to the drawings, Figure 1 is a central longitudinal section of a combined snap-hook and buckle constructed in accordance with my invention, and Fig. 2 is a perspective of the same.

Similar letters of reference indicate like parts in both figures of the drawings.

In carrying my invention into practice I propose to cast the device in a single piece, and it comprises the buckle portion A, internally recessed, as at A', and provided with the top opening A². An opening or aperture, A³, is formed in the bottom portion of the buckle, which is provided with a transverse integral pintle or bar, A⁴, to receive a tongue, A⁵, adapted when raised to project into the opening A² in the top of the buckle. At the forward end of the buckle portion A, and integral therewith, is formed the hook or arm B, which projects forwardly, upwardly, and rearwardly, like an ordinary snap-hook. At the front end of the buckle A, and at or about the juncture thereof with the hook B, is formed a recess, B², into which is adapted to be pivotally secured a tongue or snap by means of a pintle, B³, passing through apertures formed in the sides and near the rear end of the tongue or snap and into apertures B⁴, formed in the walls of the recess B².

The rear end and under surface of the snap B' is recessed, as at B⁵, for the reception of a coiled spring, B⁶, bent around the pintle B³, 50 and one end of which bears against the top portion of the hook B, and the opposite end of which bears against the under surface of the snap, forcing the same to a closed position, as usual.

A strap, C, provided with the usual perforations for the reception of the buckle-tongue, is passed into the interior recess of the buckle A, and the strap bent upwardly to permit of the tongue being inserted in one of the apertures therein, this bending operation being permissible by means of the opening A², formed in the top of the buckle. This having been done, the end of the strap, by means of the hook at its forward end, may be coupled with 65 or hooked to any object.

By reason of the tongue A⁵ projecting against the rear wall of the opening A², the former will resist strain brought upon the strap, and thus retain it in connection with the buckle. 70

If desired, other forms or modes of fastening the strap and buckle together may be provided than the tongue A⁵.

An aperture, B⁷, for escape of water, is provided in the hook B under the spring B⁶. 75

Having described my invention and its advantages, what I claim is—

1. The herein described casting, comprising the buckle portion A, recessed, as at A', B², perforated, as at A³, having the transverse bar A⁴ and the forwardly-projecting hook portion B, substantially as specified.

2. The buckle A, having the opening A², and recessed and perforated, as at A', A³, B², and B⁴, and having the transverse bar A⁴ and the hook B perforated, as at B⁷, in combination with the tongue B', pintle B³, spring B⁶, and strap D, substantially as specified. 85

In testimony whereof I affix my signature in presence of two witnesses.

CHARLES A. POMERENING.
